Primary Examiner — Shawn T Gingrich*Assistant Examiner* — Amanda Christensen(74) *Attorney, Agent, or Firm* — Kunzler Bean & Adamson; Bryan Pitt(57) **CLAIM**

The ornamental design for a magnetic charger plug, as shown and described.

DESCRIPTION

FIG. 1 is a bottom, front, right side perspective view of a magnetic charger plug showing my new design;
 FIG. 2 is a bottom, rear, left side perspective view thereof;
 FIG. 3 is a front elevational view thereof;
 FIG. 4 is a rear elevational view thereof;
 FIG. 5 is a right side elevational view thereof;
 FIG. 6 is a left side elevational view thereof;
 FIG. 7 is a bottom plan view thereof; and,
 FIG. 8 is a top plan view thereof.
 The broken lines depict portions of the magnetic charger plug, and form no part of the claimed design.

1 Claim, 8 Drawing Sheets(56)
